Inventor.
Elvie Landon, by
G. Kennedy.
Attorney.

UNITED STATES PATENT OFFICE.

ELVIE LANDON, OF WATERLOO, IOWA.

PROPELLING DEVICE FOR AEROPLANES.

Application filed July 15, 1926. Serial No. 122,689.

My invention relates to improvements in propelling devices for aeroplanes, and the object of my improvement is to supply an incased rotary propeller provided with an adjustable air receiving flue or conduit, the device having means for varying the inclination of the conduit relative to the casing, and other means for regulating the amount of air current traversing the device.

This object I have accomplished by the means which are hereinafter described and claimed, and which are illustrated in the accompanying drawings, it being understood that minor changes or modifications of the structures shown may be made within the scope of said claim.

In said drawings, Fig. 1 is a central horizontal longitudinal section of one of my propelling devices, with parts broken away. Fig. 2 is a rear elevation of the propeller casing and of the adjustable air current regulating means thereon.

The numeral 2 denotes a hollow cylindrical casing whose rear part is curvilinearly diminished at 3, providing an air piercing end to diminish frontal pressure. The flat forward wall of the casing 2 has a central aperture 4 traversed by the rear part of a propeller rotary shaft 1 which may be rotated by means of any suitable motor not shown. The rear end of this shaft within the casing is rotatably mounted in a bearing sleeve 10 integral with a supporting cross-bar 9 whose opposite ends are bolted to the opposite walls of the casing. Within the cylindrical part of the casing, fixed on said shaft 1, is mounted a hub 11 carrying radial vanes 12 set obliquely relatively to the shaft to function as propeller vanes. The outer end parts of the vanes 12 are preferably curved in the direction of rotation of the shaft except that these parts are curved with the same obliquity as the stem parts of the vanes.

The rear part 3 of the diminished casing is open and provided on opposite walls, that is, without and within, with annular bearing members 14 and 13 whose inner bearing surfaces form a zonal spherical bearing surface for an inner zonal bearing member 15, whose rear end is fastened around the forward open end of a tubular air conduit 16, so that the conduit is thus mounted for limited universal swinging adjustments upon said casing.

The numeral 5 denotes an annular inwardly flanged bearing member fastened upon the forward wall of the casing 2 concentrically about the forward aperture 4. Within this member 5 is fixed a cross plate 6 having opposite quadratate apertures, and a damper plate 7 is mounted rotatably or rockingly in said member 5 in advance of the fixed plate 6, and of like shape and provided with a handle 8, whereby the plate 7 may be rocked to vary the width of opening of the apertures in the plate 6, to thus govern the quantity of air passing through the casing 2—3 and conduit 16.

The conduit 16 may be swung adjustingly by any appropriate means, the means shown being merely illustrative of one type therefor. Staples or loops 17 may be fixed on opposite parts, quadrately, of said conduit 16 to receive looped ends of cables such as 18 and 28 on opposite sides, and at 29 at points ninety degrees apart from the first-mentioned cables. These cables are carried over sheaves 19 rotatably mounted upon the casing 2 near its junction with its diminished part 3, thence being carried over other sheaves such as 20, or 30—31 respectively to be end connected to opposite parts of the annular grooves of the winding-drums 21 and 32 respectively. Each winding drum has an operating radial handle 22, and each has a connected ratchet-wheel as at 24 and 33, the same being rotatable on short fixed shafts as at 23 projecting at different angles relative to each other from a support 35. Each ratchet-wheel has a pawl as at 25 and 34, pivoted on said support 35 and having an arm 26 with a spring connection 27 with said support, tending to keep each pawl in engagement with the teeth of the ratchet-wheel, the teeth being symmetrically anti-clinal, so that the pawl end may slip either way releasably over the teeth when the wheel is rotated in either direction.

In the operating of the device as part of the propelling mechanism of an aeroplane or other apparatus for which it is adaptable, the operator may by use of the winding drums 21 and 32, operated either singly or jointly, according to the shift of direction of the conduit 16 to be obtained, rock either or both in a way to, by means of the cables connected to the conduit, swing the conduit to any angle relative to the axis of the propeller, within the limits provided for it.

This adjustment of the conduit is to direct it in the direction which is to be given the aeroplane, so that the ejected air will effect jet propulsion in action as the aeroplane is manipulated for changes of direction, as the shift in the conduit should be one which is accommodated to the direction to be taken by the aeroplane.

The means for shifting the conduit may be other than those shown, and the relative dimensions of the conduit and the casing, as of the propeller vanes, may be varied as may be necessary for use on different species of aeroplanes, in which either speed of movement, or weight carrying capacity are the determining factors.

The air governing damper device 6—7 is to be used for regulating the amount of air current through the casing under varying conditions of use, and the damper part 7 may be actuated by means of other appliances than the handle 8 if desired. The said propelling device may be positioned upon the aeroplane according to the necessities arising from differences of construction thereof.

Having described my invention, what I claim as new, and desire to secure by Letters Patent, is:

In a device of the character described, a cylindrical hollow casing having a closed rear head with a central delivery port containing spaced segmental closure plates, rotatable segmental damper plates mounted on the casing to variably close the interspaces of the first-mentioned closure plates, the forward part of the casing being gradually diminished and terminating forwardly in a hollow spherically segmental joint member, a tube projecting forwardly from and having a rear spherically segmental joint member mounted in the first-mentioned joint member, pawl-controlled ratchet-wheel carrying winding-drums, flexible connections between said winding-drums and parts of the said tube spaced circumferentially ninety degrees apart, and an air-propeller device rotatably mounted in said casing centrally.

In testimony whereof I affix my signature.

ELVIE LANDON.
